(57) **CLAIM**

The ornamental design for a beehive pest trap, as shown and described.

DESCRIPTION

FIG. 1 is an isometric view of a beehive pest trap showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof;

FIG. 7 is a left elevational view thereof;

FIG. 8 is a front perspective view thereof;

FIG. 9 is a front-top-left perspective view thereof;

FIG. 10 is a front-top-right perspective view thereof;

FIG. 11 is a rear-bottom-left perspective view thereof; and,

FIG. 12 is rear-bottom-right perspective view thereof.

The broken lines showing cleats in FIG. 1 through 12 are included for the purpose of showing environmental structure and form no part of the claimed design.
